STABLE THERAPEUTIC COMPOSITIONS CONTAINING ACETYLSALICYLIC ACID-ANHYDRIDE

Edward H. Lincoln, Kalamazoo, Mich., assignor to The Upjohn Company, Kalamazoo, Mich., a corporation of Michigan
No Drawing. Filed Apr. 18, 1958, Ser. No. 729,258
8 Claims. (Cl. 167—55)

This invention relates to therapeutic compositions and more particularly to therapeutic compositions possessing analgesic, antipyretic and antirheumatic properties.

A wide variety of substances and compositions possessing analgesic, antipyretic and antirheumatic properties is known in the art. This variety, which includes such chemically and physiologically different substances as bromides, colchicine, hormones, iodides, addictive narcotics and salicylates, has resulted from unceasing endeavor to obtain relief from the pain and suffering accompanying the multitude of afflictions which beset human beings. Throughout the years, which can now be counted in decades, acetylsalicylic acid has gained and retained a place in the foreground through its beneficial analgesic, antipyretic and antirheumatic actions. It is believed that the said beneficial actions depend, in a large measure, on the systemic effects of the blood levels of salicylate, including the esterified compound acetylsalicylic acid.

Accompanying the beneficial properties of acetylsalicylic acid are certain chemical and physiological properties which result in distressing side-effects. Acetylsalicylic acid is known to decompose to the irritating compounds, acetic and salicylic acids. Also, acetylsalicylic acid is known to be an irritant to the gastric mucosa.

Prior to the present invention, it was not known how to provide a stable, solid therapeutic composition, in dosage unit form, which unexpectedly yields faster, higher blood levels of salicylate including the esterified compound, acetylsalicylic acid.

It is an object, therefore, of the present invention to provide therapeutic compositions which yield faster, higher blood levels of salicylate including acetylsalicylic acid. An additional object is to provide such compositions which do not form irritating amounts of acetic and salicylic acids in the stomach after oral administration. A further object is to provide such compositions which are free from mucosal irritation side-effects. A still further object is to provide such compositions which are stable under manufacturing and storage conditions. Other objects will be apparent to those skilled in the art to which this invention pertains.

The foregoing and related objects have been accomplished by the provision of a stable, solid oral therapeutic preparation in dosage unit form comprising [acetylsalicylic acid]-anhydride, and a pharmaceutically acceptable non-alkaline diluent containing a pharmaceutically acceptable acidic substance, which diluent does not lower substantially the melting point of said anhydride.

2

[Acetylsalicylic acid]-anhydride has the following structural formula:

Methods of preparation are described in *Handbuch der Organischen Chemie*, Beilstein, first edition, volume X, page 85, and in *Organic Chemistry*, Richter, volume 2, page 330, 1919. The anhydride has a melting point of 85° C. Thus, it is apparent that the chemical compound [acetylsalicylic acid]-anhydride has been available for many years. However, until the present invention, the superiority of solid [acetylsalicylic acid]-anhydride preparations in dosage unit forms was unknown and the successful preparation of said compositions was unrealized. The term "dosage unit form" as used in this specification refers to physically discrete units suitable as unitary dosages for human subjects, each unit containing a predetermined quantity of active material calculated to produce the desired therapeutic effect in association with the required pharmaceutical diluent or carrier. The specifications for the novel dosage unit forms of this invention are dictated by and directly dependent upon (a) the unique characteristics of the active material and the particular therapeutic effect to be achieved and (b) the limitations inherent in the art of compounding such an active material for therapeutic use in human beings, as disclosed in detail in this specification, being features of the present invention. Examples of suitable solid oral dosage unit forms in accord with this invention are a tablet, a capsule, a pill, a powder packet, an effervescent granule, a pilule, a wafer, a chewing gum, a cachet, a pellet, multiples of any of the foregoing, when segregated as a single dose. Forms known as the sustained-release, delayed action or enteric types are included.

The basic method of preparing the desired dosage unit form comprises mixing the active ingredient [acetylsalicylic acid]-anhydride with an appropriate diluent including an appropriate acidic substance and preparing the dosage unit form by methods and with means known in the art.

As used in the specification and claims the term "non-alkaline" is intended to mean neutral and acidic. Other than neutral and acidic, i.e., alkaline conditions, have been found to hasten deterioration of the active ingredient, [acetylsalicylic acid]-anhydride. When some of the material in the particular diluent used, or in the environment in which it is stored (including soft glass), is slightly alkaline, the presence of an acidic substance in the diluent will bring the overall environment back to substantially neutral or acidic condition with the result that the stability of the [acetylsalicylic acid]-anhydride is not affected adversely. This alkaline deterioration is more pronounced at temperatures above 25 degrees centigrade.

Substantial lowering of the melting point of the anhydride by the diluent causes deterioration of the active ingredient, in some cases actually resulting in liquefaction. The experimental data at temperatures above 25 degrees centigrade show the seriousness of this deterioration and indicate that physical and chemical deterioration will occur under some shipment and storage conditions which are often encountered in the trade.

The experimental data show that the presence of water is a problem both in the bulk mixtures used for manufacturing and in the final dosage unit forms. While deterioration from the presence of water is not immediately discernible in dosage unit forms held at 25 degrees centigrade, the data at temperatures above 25 degrees centigrade indicate that long-term stability at 25 degrees centigrade and short-term stability at temperatures above 25 degrees centigrade would be unsatisfactory. Thus, for long-term stability at 25 degrees centigrade and short-term stability above 25 degrees centigrade, substantially anhydrous dosage unit forms are preferred.

As used in the specification and claims the term "diluent" is used in reference to pharmaceutically acceptable carriers, bulking agents, excipients, binders, lubricants, adhesives, disintegrators, stabilizers (e.g., acidic substances *infra*) and the like, for example: starch, talc, sucrose, dicalcium phosphate, lactose, sorbitol, mannitol, Thixin (a highly saturated castor oil), mixtures of the foregoing, and the like.

As used in the specification and claims the term "acidic substance" is used in reference to pharmaceutically acceptable acidic substances, for example: citric acid, ascorbic acid, alkali metal bitartrates, alkali metal biphosphates, tartaric acid, malic acid, glutamic acid hydrochloride, pyridoxine hydrochloride, nicotinic acid, acidic amino acids, salts of amino acids, succinic acid, glucuronic acid, glutaric acid, pimelic acid, malonic acid, mandelic acid, adipic acid, tricarballylic acid, mixtures of the foregoing, and the like. From among this group sodium biphosphate, citric acid, pyridoxine hydrochloride, tartaric acid and malic acid are preferred.

The amount of [acetylsalicylic acid]-anhydride can be varied over a considerable range. From about 25 milligrams to about 1000 milligrams per dosage unit form can be utilized, with from about sixty milligrams to about 400 milligrams preferred. The smaller amounts are preferred in the dosage unit forms for children. The higher dosages are most useful in the rheumatic type diseases. Micronized [acetylsalicylic acid]-anhydride (i.e., having a particle size less than about ten microns) has been found to produce advantageous results.

Complementary and coacting active ingredients can be added to the compositions of this invention. Illustrative of said active ingredients are the following: acetophenetidin, caffeine, codeine and its salts, salicylamide, N-acetyl-para-aminophenol, anti-inflammatory steroids, for example, cortisone, hydrocortisone, 6-methyl-delta-1-hydrocortisone, prednisone, prednisolone, their esters and the salts of acid esters thereof, and like derivatives. Additional illustrative examples are the following: tranquilizers, antihistaminics, antitussive agents, antibiotics, sedatives and vitamins.

The compositions of this invention possess analgesic, antipyretic and antirheumatic properties and are useful in the related afflictions and disorders susceptible to such properties.

Initial attempts to prepare the compositions of the instant invention were unsuccessful. It was unexpectedly discovered that certain conventional diluents exerted deleterious effects on the active ingredient, [acetylsalicylic acid]-anhydride. Said deleterious effects were observed during the preparation of the usual dry admixtures for

subsequent manufacturing steps. It was observed that hydrolysis and deterioration of the [acetylsalicylic acid]-anhydride to the point of liquefaction occurred in some admixtures. Therefore, accelerated stability studies were performed to ascertain the compatibilities and incompatibilities of the active ingredient. These studies showed, unexpectedly, that various conventional diluents used for bulking, binding, lubrication and like actions could not be used with [acetylsalicylic acid]-anhydride. Tables I and II contain the data on the effect of the various diluents without an acidic substance.

TABLE I.—[ACETYLSALICYLIC ACID]-ANHYDRIDE STABILITY (POWDER MIXTURES)

The deleterious effects of certain of the diluents of Tables I and II are not thoroughly understood. However, it is apparent that unexpected problems had been encountered and that stability depends upon the diluents used.

Table III contains the stability data on compressed tablets comprising [acetylsalicylic acid]-anhydride and various diluents without an acidic substance.

ASA=acetylsalicylic acid.

The data of Table III indicate that short-term room temperature storage would not be harmful to the active ingredient with certain diluents, but also indicate that temperatures often encountered in shipment and storage would be harmful to preparations made without the presence of an acidic substance to counteract the alkalinity from the soft glass container and from any alkaline substance in the diluent, e.g., talc.

As is clearly shown by the foregoing stability studies on specific compositions containing a non-alkaline diluent but "not" including an acidic substance, such a compo-

40 45

sition is a substantial improvement over those containing conventional alkaline diluents. The presence of an acidic substance provides additional protection especially since it provides a greater margin of safety which neutralizes the effect of slightly alkaline conventional diluents, such as talc, and usual environmental components, such as soft glass.

Table IV contains the data on compressed tablets comprising [acetylsalicylic acid]-anhydride and a diluent containing an acidic substance which does not lower substantially the melting point of said anhydride.

ASA=acetylsalicylic acid.

These data in Table IV show that the invention is successful in providing compositions in which the active ingredient, [acetylsalicylic acid]-anhydride resists deterioration under severe temperature conditions.

Table V contains the data on stability of mixtures consisting of [acetylsalicylic acid]-anhydride and various acidic substances and stored in soft glass containers. The mixtures were prepared by granulating thirty grams of the anhydride with one gram of each of the acidic substances in twenty milliliters of water, screening, drying twenty hours at 120 degrees Fahrenheit, screening and placing in conventional amber glass bottles fitted with screw caps.

TABLE V.—MIXTURE STABILITY—[ACETYLSALICYLIC ACID]-ANHYDRIDE

Acidic Substance	One Week at 56° Centigrade		
	[ASA]-Anhydride, percent	ASA, percent	Salicylic Acid, percent
Sodium biphosphate	94.0	5.2	0.4

Citric acid	97.8	2.1	0.1
Control	72.8	16.0	0.4

¹ Liquefied.

The data in Table V show the superior stability of [acetylsalicylic acid]-anhydride resulting from the use of an acidic substance which does not affect deleteriously the melting point of the [acetylsalicylic acid]-anhydride.

Table VI contains the data on stability of mixtures consisting of [acetylsalicylic acid]-anhydride and various amounts of citric acid. The mixtures were prepared as in Table V.

TABLE VI

Grams of Citric Acid	One Week at 56° Centigrade		
	[ASA]-Anhydride, percent	ASA, percent	Salicylic Acid, percent
0.1	99.2	0.7	0.1
0.5	98.4	1.9	Neg.
1.0	97.8	2.1	0.1
2.0	98.5	1.8	0.1
3.0	100.1	1.5	Neg.
5.0	100.0	0.9	Neg.
Control	72.8	16.0	0.4

¹ Liquefied.

The data in Table VI show the superior stability resulting from the use of citric acid in an amount as small as one part to 300 parts of [acetylsalicylic acid]-anhydride.

The following examples are illustrative of the compositions of this invention but are not to be construed as limiting.

EXAMPLE 1

Compressed tablets

25,000 compressed tablets each containing 300 milligrams of [acetylsalicylic acid]-anhydride, and 10 milligrams of citric acid are prepared from the following types and amounts of ingredients:

[Acetylsalicylic acid]-anhydride   grams   7500

Granulation mixture:

Starch, bolted   do   645

d-Sorbitol solution, 70 percent   do   645

Deionized water   milliliters   5160

Citric acid   grams   250

Lubricant mixture:

Starch, bolted   do   403

Talc, bolted   do   806

The granulation is prepared by mixing the [acetylsalicylic acid]-anhydride with the sorbitol-starch paste, which contains the citric acid dissolved in the water, and drying the mixture, at about 120 degrees Fahrenheit for ten to twenty hours. After milling and screening, the granulation is mixed thoroughly with the starch-talc lubricant and compressed into tablets. Clinical testing shows that these tablets, each containing 300 milligrams of [acetylsalicylic acid]-anhydride, do not cause gastric irritation and provide superior blood levels of salicylate including the esterified compound, acetylsalicylic acid.

The addition to the above formula, per tablet, of an anti-inflammatory steroid for example, 6-methyl-prednisolone, about 0.15 to about 4 milligrams; cortisone acetate, about 2.5 to about 25 milligrams; hydrocortisone acetate, about 2 to about 20 milligrams; prednisone, about 0.25 to about 5 milligrams; 6-fluoro-hydrocortisone, about 0.15 to about 4 milligrams; 6-fluoro-prednisolone, about 0.15 to about 4 milligrams; gives a composition useful in arthritic afflictions.

Similarly, tablets containing 60, 160, 400, 600 and 1000 milligrams of [acetylsalicylic acid]-anhydride can be prepared through substituting the 7500 grams of the anhydride by the calculated amount of the anhydride.

The illustrative example contains citric acid, one of the five preferred acidic substances the others being malic acid, pyridoxine hydrochloride, sodium biphosphate and tartaric acid. The preferred amount of said acidic substances is from about one to about fifty milligrams per 300 milligrams of [acetylsalicylic acid]-anhydride.

EXAMPLE 2

Hard-filled capsules

Each capsule contains:

	Milligrams
[Acetylsalicylic acid]-anhydride	300
Tartaric acid	20
Starch, dried	120
Talc	60

The talc and starch are well mixed and incorporated with the [acetylsalicylic acid]-anhydride and tartaric acid. The whole mixture is milled and screened through a sixty to eighty mesh screen. The capsules are subsequently filled, by means and methods known in the art, into capsules.

Fifteen to thirty milligrams of the talc can be substituted by Thixin, a finely powdered highly hydrogenated castor oil, to give an equally satisfactory capsule.

EXAMPLE 3

Chewing gum

Pieces of uncoated chicle chewing gum weighing approximately one gram each are used as starters for the coating process. A coating of sucrose is first applied, using a syrup containing approximately eighty percent of sucrose by weight, in the usual coating pan. A finely powdered highly hydrogenated castor oil (Thixin), is then dusted on the sucrose-covered starters. The second coating step uses a dispersion of micronized [acetylsalicylic acid]-anhydride and pyridoxine hydrochloride in absolute ethanol. This suspension adheres to the oil layer and permits rapid drying between successive coatings with the active ingredient. Eight to ten successive coatings are applied to give a gum containing fifty milligrams of [acetylsalicylic acid]-anhydride. Thereafter, a second dusting with the hydrogenated castor oil is applied.

The final finishing and protective coatings contain flavor, coloring and polishing ingredients. It is preferred to apply a final water-proof-preserved type of coating, for example, carnauba wax.

EXAMPLE 4

Powder packet

A powder packet is prepared from the following types and amounts of ingredients:

Each packet contains:

	Milligrams
[Acetylsalicylic acid]-anhydride	1000
Starch, dried	150
Malic acid	40
Talc, dried	200

The ingredients are mixed and milled to a particle size of approximately forty mesh and filled into plastic-coated paper or aluminum foil packets. The ingredients in such packets are satisfactory for preparing a dispersion in water, milk, fruit juices and the like, for oral administration.

EXAMPLE 5

Hard-filled capsule

Following the procedure of Example 2, capsules are prepared containing 228 milligrams of [acetylsalicylic acid]-anhydride from 70 to 160 milligrams of acetophenetidin and from sixteen to 35 milligrams of caffeine per capsule.

EXAMPLE 6

Compressed tablet

Following the procedure of Example 1, tablets are prepared with a complementary active ingredient by adding 10 to 30 milligrams of codeine sulfate per 300 milligrams of [acetylsalicylic acid]-anhydride, granulating and compressing by the method shown.

EXAMPLE 7
Compressed tablet

Following the procedure of Example 1, tablets are prepared with a complementary active ingredient by adding 50,000 to 250,000 units of potassium penicillin V per 300 milligrams of [acetylsalicylic acid]-anhydride, granulating and compressing by the method shown.

EXAMPLE 8
Hard-filled capsule

Following the procedure of Example 2, capsules are prepared with a complementary active ingredient by adding from about 0.25 to about one milligram of reserpine per capsule.

EXAMPLE 9
Hard-filled capsule

Following the procedure of Example 2, capsules are prepared with a complementary active ingredient by adding 1 to 4 milligrams of chlorpheniramine maleate per capsule.

EXAMPLE 10
Compressed tablets

Following the procedure of Example 1, a compressed tablet is prepared containing in each tablet:

	Milligrams
[Acetylsalicylic acid]-anhydride	300
6-methyl prednisolone	1
Citric acid	10

Ascorbic acid, ten milligrams per tablet, can be added to the above formula.

It is to be understood that the invention is not to be limited to the exact details of operation or compositions shown and described, as obvious modifications and equivalents will be apparent to one skilled in the art, and the invention is therefore to be limited only by the scope of the appended claims.

What is claimed is:

1. A stable, solid oral therapeutic preparation in dosage

unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

2. A substantially anhydrous, stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

3. A stable, solid oral therapeutic preparation in dosage unit form comprising from about 25 to about 1000 milligrams of [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

20 4. A stable, solid oral therapeutic preparation in dosage unit form comprising from about 25 to about 1000 milligrams of [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

25 5. A stable, solid oral therapeutic preparation in dosage unit form comprising from about 25 to about 1000 milligrams of [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

30 6. A substantially anhydrous, stable, solid oral therapeutic preparation in dosage unit form comprising an anti-inflammatory steroid, from about sixty to about 400 milligrams of [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

35 7. A substantially anhydrous, stable, oral therapeutic tablet comprising one milligram of 6-methylprednisolone, 300 milligrams of [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

40 8. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

45 9. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

50 10. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

55 11. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

60 12. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

65 13. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

70 14. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

75 15. A stable, solid oral therapeutic preparation in dosage unit form comprising [acetylsalicylic acid]-anhydride and a pharmaceutically acceptable non-alkaline diluent containing from about 0.3 to about 17% by weight of said anhydride of a pharmaceutically-acceptable acid-reacting stabilizing compound to stabilize the preparation against decomposition by alkali, which diluent does not lower substantially the melting point of said anhydride.

11

carballylic acid, and mixtures thereof, which diluent does not lower substantially the melting point of said anhydride.
